NARCISSE E. LALIBERTÉ, OF HAVERHILL, MASSACHUSETTS, ASSIGNOR TO HAMEL SHOE MACHINERY COMPANY, OF HAVERHILL, MASSACHUSETTS, A CORPORATION OF MASSACHUSETTS.

BOBBIN-CASE LOCK.

1,414,026.

Specification of Letters Patent. Patented Apr. 25, 1922.

Application filed August 1, 1918. Serial No. 247,733.

To all whom it may concern:

Be it known that I, NARCISSE E. LALIBERTÉ, a citizen of the Dominion of Canada, residing at Haverhill, county of Essex, State of Massachusetts, have invented a certain new and useful Improvement in Bobbin-Case Locks, of which the following is a specification, reference being had therein to the accompanying drawings.

10 My invention relates to shoe sewing machines of the type employing a loop-taker and a thread-case therein and has to do particularly with means for holding the thread case in place within the loop-taker. As is 15 well understood by those skilled in the art, the bobbin case must be held securely in place but in such a manner that it can be removed and replaced whenever the thread is exhausted. As it is necessary to frequently 20 change the thread within the thread case, it is important to have a thread case lock which permits the thread to be replaced with a minimum expenditure of time and effort. The device embodying my invention holds 25 the thread case positively in place at all times and the parts are so constructed that there is nothing to get out of order or to wear.

The invention will be fully understood 30 from the following description when taken in connection with the accompanying drawings and the novel features thereof will be pointed out and clearly defined in the claims at the close of this specification.

35 In the drawings, Fig. 1 is a view in elevation of my improved thread case lock applied to a sewing machine of the type referred to.

Fig. 2 is a section on line 2—2 of Fig. 1. 40 Referring now to the drawings, at 11 is shown a shuttle race or housing within which is the loop-taker in the form of a shuttle 12. The shuttle 12 is operated by the shaft 13 and a gear 14 in a manner not 45 necessary to be described in detail. Inside the shuttle 12 is the bobbin or thread case 15 which is shown containing a bobbin 16. As is customary in sewing machines of this character, the front face of the shuttle, that 50 is, the face on the left hand side of Fig. 2 is open for the removal of the bobbin case and the bobbin case is provided at 18 with a pro-

jection in which may be located the hole 19 through which the thread from the bobbin is withdrawn.

55

At 20, 20 is shown a pair of lugs on the front face of the shuttle housing or support 11. At 21 is pivoted to these lugs a slightly curved arm or bar 23 axially forked at its lower end as shown at 24. The fork is so 60 proportioned that it will straddle the projection 18 on the end of the bobbin case, and will thus keep the bobbin case from rotating with the shuttle 12 as would otherwise be its tendency. By reason of the suspension of the 65 retaining arm 23 from a point near its upper extremity, it is clear that this arm tends, under the action of gravity, to resume substantially its normal position, as shown in Fig. 2, thus materially assisting the operator 70 in restoring the parts to normal working position, while at the same time avoiding the necessity for the use of positive stops for determining the operative position of the arm.

When the arm 23 is in the position shown 75 in full lines in Fig. 2, there is a space between its upper end and the face of the shuttle housing 11. A freely movable gravity-actuated latch 4 is pivoted at 25, this latch being provided with a portion arranged

80

to drop into the space between the upper end of the arm 23 and the forward face of the shuttle housing. The latch 4 is provided with a suitable finger-engaging member whereby it may be lifted out of said space.

85

The operative portion of the latch 4 constitutes a spacing element or stop which engages the arm 23 at spaced points at opposite sides of the pivot-pin 21 so as to prevent the approach of either of these points 90

95

toward the shuttle-race or support and thereby prevent movement of the thread-case-engaging outer portion of the arm 23 either toward or from the thread-case. The sides of the latch are substantially parallel and its thickness is about that of the space.

95

The latch extends down into the space to a point below the pivot 21 of the arm. When the latch is in place, the arm 23 cannot be lifted up in the direction of its position shown in dotted lines in Fig. 2, because the portion of the arm designated a strikes the latch; neither can it be pushed in further

100

toward the bobbin case because the portion

of the arm designated *b* then strikes the latch. The arm is thus positively held against movement in either direction from the position which it normally assumes, as seen in Fig. 2, the use of a single locking element simultaneously engaging the arm upon opposite sides of its pivotal axis, thus accomplishing in a very simple and effective manner the results which heretofore have been attained only by the use of complicated and cumbersome devices. While it is within the scope of the invention to arrange a latch member for engagement with the front side of arm 23, it is regarded as distinctly advantageous to locate any such locking device to the rear of said arm as herein shown, it being desirable in all cases to minimize the projection of parts from the forward face of the shuttle housing, wherever this is possible.

To remove the bobbin case, the latch is moved to the position shown in dotted lines in Fig. 1, and the arm 23 lifted up. To restore the parts to normal position, the operator taking the bobbin case in his hand, lifts the retaining arm 23 and pushes the bobbin case into the shuttle. The retaining arm now drops freely into substantially operative position automatically, and by a single movement of the finger the latch 4 may be thrown over into position to drop into the space behind the arm 23, whereby the arm is positively locked in proper position.

By the arrangement of parts herein shown, the bobbin case is positively retained in proper position by the use of but two movable elements, each of which is of simple form and of easy construction and which can be manipulated by the operator with little expenditure of time or attention.

Having thus described the invention and a preferred embodiment of the same, what I claim and desire to secure by Letters Patent of the United States is:—

45 1. In combination, a loop-taker, a thread-case therefor, a support relative to which the loop-taker performs its operative movements, a pivotally mounted thread-case retaining member partially overlying said support, and a stop-member movable into and out of operative position between said retaining member and support.

55 2. In combination, a loop-taker, a thread-case therefor, a support relative to which the loop-taker performs its operative movements, a pivotally mounted thread-case retaining member partially overlying said support, and a stop-member movable into and out of operative position between said retaining member and support and adapted to engage said member at spaced points at opposite sides of its pivot.

60 3. In a sewing machine having a stationary support, in combination, a loop-taker, movably supported by said support, a bobbin

case within the loop-taker, a freely movable gravity-actuated member for retaining said bobbin case within the loop-taker, and a freely movable, gravity-actuated means for holding said member in retaining position. 70

4. In a sewing machine having a stationary support, in combination, a loop-taker rotatably supported in said housing, a bobbin case within the loop-taker, and means for retaining the bobbin case within the loop-taker comprising a bar pivoted for movement substantially in a plane in which the axis of the loop-taker lies and engageable with said support, and a freely movable, gravity-actuated latch member for retaining said bar in operative position. 75

5. In a sewing machine, in combination, a rotatable loop-taker, a bobbin case within said loop-taker, a bobbin case retaining arm pivotally mounted at one side of the bobbin 85 case to swing toward and from the plane of the latter's face, and a latch constructed and arranged to move into and out of engagement with the retaining arm upon the opposite side of its pivotal axis from that portion of said arm which engages the bobbin case. 90

6. A sewing machine having, in combination, a bobbin case, a retaining member for said bobbin case swingable about a fixed pivot 95 whereby to bring an element thereof into retaining engagement with said bobbin case, and a latch for said retaining member movable into and out engagement with that side thereof which is presented toward the bobbin 100 case.

7. In a sewing machine, in combination, a bobbin case having its axis extending from front to rear, a retaining arm for said bobbin case swingable about a fixed pivot substantially in a plane in which the axis of the shuttle lies, said arm having near its free extremity an element arranged for operative contact with the bobbin case, and a pivotally mounted latch member for said arm mounted 105 to swing in a plane at right angles to the axis of the bobbin case and to the rear of said arm.

8. In combination with a stationary shuttle housing, a rotating shuttle, a bobbin case 115 inside the shuttle, a bobbin case retaining arm pivoted on a stationary part of the machine, and a latch engaging a surface of the arm on opposite sides of the pivotal axis thereof so that the arm cannot be swung in 120 either direction when the latch is in place.

9. In combination with a shuttle housing, a shuttle, a bobbin case inside the shuttle, a bobbin case retaining arm pivoted between a pair of fixed lugs, there being a space between the said arm and the shuttle housing, and a latch adapted to move into the said space and to hold the arm in position adjacent the bobbin case. 125

10. In a sewing machine, in combination, 130

a shuttle housing, a shuttle rotatably supported therein, a bobbin case within the shuttle, a pair of spaced lugs projecting outwardly from the upper portion of the shuttle
5 housing, a bobbin-case retaining arm pivotally mounted between said lugs and depending therefrom, said arm provided near

its free extremity with a bobbin case engaging element, and a locking latch for said arm provided with a member constructed and 10 arranged to be positioned between said arm and the adjacent face of the shuttle housing.

In testimony whereof I affix my signature.

NARCISSE E. LALIBERTÉ.
